(57) **CLAIM**

The ornamental design for a intelligent control box, as shown and described.

DESCRIPTION

FIG. 1 is a first perspective view of an intelligent control box according to a first embodiment of my new design;

FIG. 2 is a second perspective view of the intelligent control box, according to a first embodiment of my new design;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a first perspective view of an intelligent control box according to a second embodiment of my new design;

FIG. 10 is a second perspective view of the intelligent control box according to the second embodiment of my new design;

FIG. 11 is a front view of the intelligent control box according to the second embodiment of my new design;

FIG. 12 is a rear view of the intelligent control box according to the second embodiment of my new design;

FIG. 13 is a left view of the intelligent control box according to the second embodiment of my new design;

FIG. 14 is a right view of the intelligent control box according to the second embodiment of my new design;

FIG. 15 is a top view of the intelligent control box according to the second embodiment of my new design;

FIG. 16 is a bottom view of the intelligent control box according to the second embodiment of my new design;

FIG. 17 is a perspective view of the intelligent control box in use with the light strip for reference, according to the first embodiment of my new design; and,

FIG. 18 is a perspective view of the intelligent control box in use with the light strip for reference, according to the second embodiment of my new design.

The broken lines in the drawings show portions of the intelligent control box which form no part of the claimed design.

1 Claim, 18 Drawing Sheets
